United States Patent Office

Des. 205,019
Patented June 7, 1966

205,019

BOAT

Walter T. Heintze, Lewisboro, N.Y.
(R.R. 1, New Canaan, Conn.)

Filed May 18, 1965, Ser. No. 85,345

Term of patent 7 years

(Cl. D71—1)

FIG. 1

FIG. 1 is a left rear perspective view of a boat embodying my new design;

FIG. 2 is a right side elevational view thereof; and FIG. 3 is a front elevational view thereof.

The dominant features of my design reside in portions shown in full lines.

I claim:

The ornamental design for a boat, as shown and described.
